MIXING APPARATUS

George W. Newton and Paul R. Powell, Baltimore,
Md., assignors to Crown Cork & Seal Company,
Inc., Baltimore, Md., a corporation of New York

Application September 23, 1940, Serial No. 357,974

15 Claims. (Cl. 259—54)

The present invention relates to a mixing apparatus and, more particularly, to an apparatus for mixing the contents of soft drink containers.

The present structure is an improvement upon the apparatus disclosed in George W. Newton Patent No. 2,216,090, issued September 24, 1940, for Mixing method and apparatus.

In filling soft drink containers, it is usual to first flow the proper amount of syrup into the bottom of the container and then flow into the container a charge of carbonated water having five or six times the volume of the syrup. Since the syrup is heavier than the carbonated water, it tends to remain at the bottom of the container and, because of the syrup thickness, it is necessary to bodily move the container in order that the syrup will be thoroughly intermingled with the water.

The above-mentioned Newton patent discloses an apparatus comprising a rotary table including a number of container or bottle supporting elements which are rotatable in a plane radial of the table, each bottle supporting element including a bottle supporting platform and a reciprocable clamping head. At the point during the rotation of the rotary table where a bottle will be delivered to a bottle supporting element, the element is held upright and the clamping arm is held raised. Immediately subsequent thereto, and during the continued rotation of the rotary table, the clamping arm descends to lock the bottle in place and the supporting element is then swung through approximately 180° in a vertical plane so as to invert the bottle and cause the syrup to flow longitudinally.

The platforms and clamping heads of the bottle supporting elements are rotatable with respect to the remainder of these elements and during the time that a bottle is in inverted position, the platform is rotated to cause the container and its contents to spin about the longitudinal axis of the container so that the contents will be thoroughly mixed. This spinning is subsequently stopped, the bottle supporting element uprighted and the clamping head raised so that the bottle may be removed from the rotary table.

Because of the high speeds at which mixing apparatus are operated, it is extremely important that the bottles be firmly clamped in centered position in the container supporting elements, otherwise the spinning movement, ranging from approximately 800 to 1500 revolutions per minute, may cause the bottles to be ejected from the machine.

The problem of centering bottles is increased by reason of the fact that the rotary table is rotated at fairly high speed and bottles must be transferred onto the bottle supporting elements of the table during such rotation. Therefore, the slightest impedance in the path of a bottle may cause it to be slightly off-center in the supporting element.

An important object of the present invention is to remove all interference with the transfer movement of containers and also the provision of positive means to center each container in the supporting elements and securely hold it so that it can be tilted and spun at high speed without any possibility of becoming loose from the apparatus.

A further object is the provision of a container supporting platform which is freely rotatable with respect to its container supporting element and upon which a container can be quickly moved and centered without any possibility of being upset during such movement, as well as during reverse movement.

A still further object is the provision of a container supporting plate which will be flush with the stationary table of the apparatus during the time that containers are moving to and from the container supporting elements and which will also center all sizes of containers.

Another object of the invention is to provide a container top clamping means which includes a readily rotatable element to firmly hold the top of a container.

A further object is to provide means particularly designed to positively engage the upper portion of a container during transfer movement to and from a container supporting element.

Heretofore, most bottle handling machines of the rotary table type, including filling machines, have simply included means to engage the lower portion of a container during transfer movement. The present apparatus includes means to also engage and guide the upper portion of the container, thereby entirely obviating the possibility of a container being upset during transfer.

Another object is to provide means to cooperate with the container supporting elements to insure that every container will be accurately centered therein before spinning movement is initiated.

A further object of the invention is to provide container centering means fixed on the container supporting elements to receive the lower portion of the bottles and center the same.

Another object of the invention is to provide an

efficient and economical arrangement for controlling the tilting movement of the container supporting elements.

It has heretofore been proposed to control such tilting movement by a rack and pinion connection between the bottle supporting element and a sliding element reciprocated by a stationary cam. In other arrangements, such movement has been controlled by shafts geared to the container supporting element. The present invention involves the use of a sliding element reciprocated by a stationary cam and connected to the bottle supporting element by a flexible chain. It is found that this arrangement is much simpler than prior arrangements, is readily adjustable, and results in extremely efficient operation.

A still further object of the invention is to provide a means for controlling the operation of the clamping head and which means also has the function of insuring that the container supporting elements will remain in upright position during the transfer operation.

In prior apparatus, it has been usual to provide a separate cam track on the fixed portion of the machine and to equip each container supporting element with a roller or guide element to follow this track during the time that the element is in upright position for transfer of bottles.

By the present arrangement, this separate cam track and roller are eliminated and the bottle is securely held in upright position by the clamping arm operating means.

The above-mentioned arrangement is of such design that long use of a machine cannot result in the mechanism having play and thereby causing the container supporting elements to have a slightly tilted position during the critical transfer operation.

A still further object of the invention is to provide an improved arrangement for spinning the containers or bottles, as well as a simple and readily removable mounting for the same.

Other objects and advantages of the invention will be apparent from the following drawings wherein:

Figure 1 is a radial section through the front portion of a machine of the general type disclosed in the above-mentioned Newton patent, the view showing the mechanism for tilting the container supporting elements in vertical section,

Figure 2 is a vertical sectional view of the rear portion of the rotary table, with portions in side elevation,

Figure 3 is a detail view showing the clamping arm controlling means in the position which it will occupy immediately after a container supporting element has been uprighted but before clamping, the view being taken from behind Figure 1,

Figure 4 is an enlarged vertical section of a container supporting element tilting mechanism,

Figure 5 is a top plan view, with portions in horizontal section, of a container top clamping arm,

Figure 6 is a side elevation, partly in vertical section, of a container supporting element,

Figure 7 is a vertical sectional view through the body element of a bottle supporting platform,

Figure 8 is a side elevation, partly in vertical section, of the top clamping portion of a bottle supporting element,

Figure 9 is a horizontal sectional view on the line 9—9 of Figure 6,

Figure 10 is a plan view of the major portion of the cam structure of the apparatus,

Figure 11 is a development of the front portion of the cam shown in Figure 10, with the front central portion thereof omitted, and

Figure 12 is a horizontal sectional view on the line 12—12 of Figure 1.

Referring to Figure 1, the numeral 15 designates the stationary worktable which is provided at the front of the machine. A base section 15a projects rearwardly from the stationary worktable and includes a suitable vertical journal for the rotary table 16 which is driven through suitable driving connections. As is described in the above-mentioned Newton patent, the stationary table 15 is provided with a driven infeed dial 17 and an outfeed dial, not shown. The infeed dial 17 delivers a container to one of the bottle supporting elements generally designated by the numeral 18 which are spaced about the periphery of the rotary table 16 and the outfeed dial subsequently removes containers from these elements. Sixteen container supporting elements 18 are usually provided and, as best shown in Figure 1, each container supporting element 18 is mounted upon one of a series of spaced upstanding housings or hollow posts 19 fixed to the periphery of the rotary table, the container supporting elements including horizontally extending shafts 20 which extend into and are journaled in the upper portions of the housings 19 so that the container supporting elements may rotate alongside such housings in a plane radial of the table 16. This movement is indicated by the upright position of a container supporting element in Figure 1 as compared with its inverted position indicated in Figure 2.

Referring to Figure 6, each container supporting element 18 includes a tubular portion 25 having the stub shaft 20 fixed in its upper end. The lower portion of tubular element 25 includes an integral outward extension 26 having its outer end of cup-shaped form as indicated at 27. The central portion of the cup 27 is apertured as indicated at 28 to receive a pin 29 which is headed to bear upon the inner ring of a bearing assembly 30 mounted in the cup portion. Each cup member 27 has mounted therein a container supporting platform 31 including a plate 32. As best shown in Figure 7, each platform 31 is of cup-like form and includes a circular depending skirt 33 and arms 34 extending inwardly and downwardly from its upper portion, which arms support a downwardly flanged portion 35 including a depending sleeve 36.

As shown in Figure 6, the sleeve 36 of each platform 31 surrounds the outer ring of the bearing assembly 30 so that the platform will rotate with such ring. The platform is held to the ring by a suitable locking element shown in Figure 6 and positioned in the annular groove 37 at the lower portion of the inner surface of sleeve 36. The top wall of portion 35 is spaced very slightly above the upper end of the pin 29, and it will be noted that the outer surface of sleeve 36 is spaced slightly within the upstanding flange of the cup 27 so as to rotate freely within such cup.

The bottle supporting plate 32 is, as best shown in Figure 9, of spider form and is so positioned within platform 31 that its radial outwardly and downwardly extending arms 38 alternate with the inwardly and downwardly extending arms 34 of the platform. The outer ends of the plate

arms 38 bear upon the upper end of a relatively light coil spring 39 positioned with the platform 31, the lower end of coil spring 39 bearing upon a flange 40 of the platform. Spring 39 serves to normally hold the upper surface of plate 32 flush with the upper edge of platform 31 and the facing edges of the platform and plate are bevelled as indicated in Figure 6 so that no sharp corners will be in the path of the bottles sliding to and from the plate 32.

The forward extension 28 of each container supporting element 18 carries a roller 42 for a purpose hereinafter set forth.

The container clamping arm 45 included in each bottle container supporting element is illustrated in detail in Figures 5 and 6 and is fixed to the upper end of a rod 46 extending downwardly into the tubular housing 25 of the element. The lower end of rod 46 is enlarged to form an upwardly facing shoulder 47 and a coil spring 48 extends between this shoulder and the upper inner portion of the housing 25 with the result that the rod and clamping arm 45 will normally be urged toward the container supporting plate 32. The lower portion of rod 46 has a conical recess 49 therein adapted to be engaged by an element 50 hereinafter described which will raise the rod and clamping arm against the action of spring 48. The reciprocating movements of the clamping arm 45 and rod 46 in the housing 25 are guided by a bar 51 secured in the clamping arm 45 and adapted to move through an aperture 52 in housing 25. As shown in Figure 8, bar 51 is connected to rod 46 by a plate 53 pinned to the rod and which limits the downward movement of clamping arm 45 with respect to housing 25. As indicated in Figure 6, in the downward and clamping position of arm 45, with a bottle beneath this arm, the plate 53 will still be spaced somewhat above the upper end of housing 25.

The outer end of each clamping arm 45 has the form of a downwardly facing cup as indicated at 55 and a bearing assembly 56 is mounted in this cup. The outer ring of bearing assembly 56 rests upon an annular ring 57 which includes lower diverging arms 58 and 59, these arms being carried by the ring at a point beneath the lower edge of cup 55. The rearward portion of cup 55 extends further downwardly as indicated at 60 and a pin 61 connects the rear portion of the wings to the extension 61 so as to lock the ring 57 in place. The inner ring of bearing assembly 56 has fixed thereto a bottle cap engaging element 63 including a shank 64 carrying a wire which bears upon the top of the bearing assembly. Cap engaging element 63 has a downwardly facing recess therein of a form to snugly engage a crown cap sealed upon a container.

Figure 8 shows a slightly modified form of cap engaging element 63a which includes a water guard 65 for bearing assembly 56. Figure 8 also shows the bar 51 fixed to housing 18 and movable through an aperture in arm 45.

As indicated in Figure 5, the wings 58 and 59 extend outwardly in such directions as to guide movements of the tops of bottles to and from centered position on the plate 32. As indicated by the line "in" on Figure 5, during its movement beneath the clamping arm 45, the top of a bottle will move adjacent wing 58, the wing being sufficiently flared so as to insure that the top of the bottle will be directed beneath the top engaging element 63. As indicated by the line "out," an outgoing bottle will have its top move adjacent the wing 59.

In order that the lower portions of bottles may be more readily centered upon the plate 32, a limit plate 66 extends outwardly from the lower portion of each housing 25, the outer edge of the plate being cut away on an arcuate line as indicated at 67 in Figure 12 to limit the inward movement of a bottle on the plate 32 and thereby center the bottle.

As is described in the above-mentioned Newton 10 patent, during the time that a container supporting element 18 is adjacent the front and stationary table 15, it will be held in the upright position illustrated in Figure 1 so that a container may be placed upon the plate 32. At this time, the upper edge of platform 31 as well as the upper surface of plate 32 will be flush with the upper surface of the stationary table 15. Thereafter, the container supporting element will be turned to the inverted position shown in Figure 2 with the result that the roller 42 normally positioned downwardly as shown in Figure 6 will be brought into contact with the arcuate guide rail 70 as illustrated in Figure 2. Guide rail 70 is spring mounted on brackets fixed to the underside of a cover-plate 71 mounted on posts such as 72 extending upwardly from the base of the machine outwardly of rotary table 16. Rail 70 serves to hold each rotary platform 31 in contact with the friction surface of a wheel 73 journaled on a central and fixed stub shaft 74 extending down from plate 71. As shown in Figure 1, wheel 73 includes an upper pulley portion engaged by a belt 75 driven at high speed by a motor 76 suspended in an opening in plate 71. The motor is adjustably mounted so that its position may be varied to keep belt 75 under proper tension.

Wheel 71 has its upper and inner portion stepped to interfit with a corresponding portion of cover-plate 71 to form a labyrinthine joint 77 and thereby prevent water thrown from the rapidly spinning bottles from moving down along stub shaft 74.

Each container supporting element 18 will move approximately 210° with the table in the inverted position shown in Figure 2 and the container will be spun by wheel 73 at an approximate speed of from 800 to 1500 revolutions per minute as described in the above-mentioned Newton patent. At the conclusion of this spinning movement, the roller 42 of the container supporting element will move clear of the outfeed end of rail 70 so that the container supporting element may be returned to upright position before it comes opposite the outfeed dial of the machine to have the container removed therefrom.

In order to control the movement of the container supporting element from the upright position shown in Figure 1 to the inverted position shown in Figure 2 and again return it to upright position, a rod 80 is mounted within each housing or hollow post 19 of rotary table 16 and is suitably connected by a link chain 81 to the shaft 20, journaled in housing 19, which serves as the axis for the above-described turning or tilting movement of each container supporting element 18. By this arrangement, reciprocating motion of the rod 80 will be transmitted through the chain 81 to shaft 20 so as to rotate the shaft in the housing 19 and thereby turn the corresponding container supporting element 18 from the position shown in Figure 1 to that of Figure 2 and then return the element to upright position. Referring to Figure 4, in order that the chain 81 will have no play during its movement, a block 83 is secured within the upper portion of each housing

19, this block including an arcuate lower end which bears upon the rollers of the chain, the flanges of the chain rollers moving along the side edges of the block. Similarly, a block 84 has its arcuate upper end bearing upon an enlarged portion 85 of shaft 20, the inner side surface of the block 84 contacting with the rollers of the chain links and the roller flanges riding along the block. Chain 81 has a pin connection with the upper end of the plunger 80 and its upper end carries a slotted plate 81a which is secured to shaft 20 by a pin 86 extending through the slot and into a radial bore in the enlarged portion 85 of the shaft.

As shown in Figures 1 and 2, the lower end of each rod 80 carries a roller 88 which moves in a circular and fixed cam track 89 formed in a casting or series of castings 90 secured to the stationary portion 91 of the base 15a of the machine beneath the peripheral edge of rotary table 16. The cam track 89 is of a form identical with that disclosed in the above-mentioned Newton patent. That is, as best shown in Figures 10 and 11, cam track 89 includes a low portion 89a extending for approximately 210° of the path of rotation of table 16, this low portion of the cam being at the rear part of the machine. With the rotary table 16 turning in the direction of the arrows in Figures 10 and 11, a roller 88 on the rod 80 will be in the low portion 89a to hold the 30 bottle inverted as illustrated in Figure 2 throughout approximately 210° of the movement of the container with the table. Then, as a container supporting element 18 approaches the stationary table 15, the roller 42 of the container supporting element will move off the outfeed end of the guide rail 70.

Immediately after roller 42 has moved out of engagement with guide rail 70, rod roller 88 will move up the incline 89b (Figures 10 and 11) of cam track 89 so as to raise rod 80 from the position indicated in Figure 2 to that of Figure 1. The raising of rod 80 will cause shaft 20 to rotate in a clockwise direction with respect to Figure 2 so that the container supporting element will 45 turn in a similar direction to return to the upright position of Figure 1. It will be noted that because the upper block 83 prevents chain 81 from slacking, the movement imparted to shaft 20 by the raising of rod 80 will be positive. In 50 any event, a container supporting element 18 cannot swing in a counterclockwise direction as viewed in Figure 2 because the spinning platform 31 is in contact with the spinning wheel. Also, centrifugal effect set up by the rotation of table 16 urges the container supporting elements to swing 55 outwardly away from wheel 73 until they reach a horizontal plane and then the weight of the elements urges them to a vertical and upright position. As a result, chain 81 is under tension during the entire lifting of rod 80 and no play to cause sudden jerking can occur. When roller 88 reaches the high portion 89c of Figure 10, the container supporting element will have the upright position shown in Figure 1. At this time 60 platform 31 may contact with a friction shoe to have its spinning terminated as described in said Newton patent.

The container supporting element will continue in the upright position just described until the 70 roller 88 moves down the decline 89d, thereby causing the rod 80 to be moved downwardly from the Figure 1 position to the Figure 2 position so that the element 18 will be inverted.

In order to lift and then lower the container 75

clamping arm 45 during the time that the container supporting element 18 is held upright as in Figure 1, a second cam track 95 is formed on the front portion of casting 90 to actuate a roller 96 carried at the lower end of each plunger 50 as shown in Figures 2 and 3.

Figure 6 shows the rod 46 within element 18 in the clamping position which it will occupy during all tilting movement of the container 10 supporting element as well as during the time that an element is inverted as in Figure 2. During all this time, the plunger 50 which is aligned radially of the table 16 with the rod 46 will be held downwardly by gravity in the vertical bore 97 in table 16 in which it reciprocates. As shown in Figure 2, at such time the lower end of plunger 50 simply rests upon a ledge 98 on the inner side of the downwardly extending skirt 105 of the table 16, its roller 96 moving beneath a rib 99 on casting 90. However, as illustrated in Figure 11, rib 99 leads to cam track 95 which includes an incline 95b, a dwell 95c and a decline 95d along which the roller 96 will move during the time that a container supporting element is in upright position. The actuation of this portion of the mechanism is as follows: When a container supporting element has been moved to an upright or substantially upright position by reason of the fact that the associated element rotating rod 80 has reached the rise 89c of cam track 89, the clamping controlling plunger 50 will have the position with respect to the upper plunger that is indicated in Figures 3 and 6. That is, the upper end of the plunger 50 will be out of contact with the socketed end 49 of rod 46, this position permitting the container supporting element to move to a substantially upright position from that of Figure 2. However, immediately element 18 has reached substantially upright position, the roller 96 of clamping controlling plunger 50 will move into the incline 95b of cam track 95 so that plunger 50 will rise to contact with the socketed end 49 of rod 46, thereby locking the entire element 18 against any swinging movement and, by continued lifting, also lifting the clamping arm 45 against the action of its spring 48.

As is described in the above-mentioned Newton patent, the bottle which has been mixed will then be removed from the plate 32 by the usual outfeed dial and a second bottle inserted by the infeed dial 17. Dwell 95c of cam track 95 is sufficiently high to insure that the clamping arm will be raised an adequate distance, though it will be observed that the clamping arm 45 can have its position adjusted on rod 46 for bottles of various heights.

Immediately after a bottle has been positioned on the plate 32 by the infeed dial, roller 96 will move down decline 95d so as to draw plunger 50 to the position illustrated in Figures 3 and 6 so that clamping arm 45 may be lowered by spring 48 to clamp the bottle. Then roller 88 of element turning plunger 80 will move down decline 89d of cam track 89 to turn the bottle to inverted position. Since plunger 50 is drawn entirely clear of the lower end of upper plunger 46, the turning movement of the element will not be interfered with by plunger 50.

It will be noted that the provision of the plunger 50 to control the lifting of clamping arm 45 likewise comprises a means to hold the container supporting elements locked in upright position while containers are being transferred.

In order that the top portions of containers

will be positively centered in the clamping heads 45, an arm 100 (Figures 5 and 6) is provided on a rod 101 extending down from the front portion of cover plate 71. Referring to Figure 5, a coil spring urges an arm 100 in a clockwise direction and each bottle passing the arm, just before clamping arm 45 has reached entirely lowered position, will have its upper portion brushed by the arm as indicated in Figure 6 so that the entire bottle will be urged to properly centered position. Also, the lower edge of spinning wheel 73 includes an outwardly extending flange 102 which, as shown in Figure 2, will contact with the base portion of inverted bottles. That is, when a container supporting element first reaches inverted position, the base portion of the bottle carried thereby will contact with flange 102 and if the bottle is not centered at this portion, the flange will move it to such position.

It is found that the provision of the cover plate 71 prevents water thrown from the bottles during spinning from being distributed about the bottling plant. The high speed spinning has a very favorable action in drying bottles so that labels can readily be applied to them. More particularly, bottles are washed immediately before being filled, and are usually wet when subsequently moving through the labeler. However, the positioning of the present machine immediately adjacent the filler, and with the labeler close to the outfeed of the mixer, with an inspection machine perhaps interposed, insures that bottles will be dry when they reach the labeler.

The depending skirt 105 of table 16 may have vertical guideways, not shown, fixed on its inner wall to guide the vertical movements of the plungers 50 and 80. This skirt serves to enclose the cam track and plungers.

The structure of the container supporting platforms 31 including the spring pressed plates 32 is extremely efficient in that it enables containers to be held under spring tension and in a recess during tilting and spinning movement. It will be particularly observed that the inwardly and downwardly extending arms 34 of the platform 31 serve to center the containers carried upon the spring pressed plates 32. That is, as a container is pressed downwardly with the plate 32 by the descent of the clamping arm 45, the container will likewise be moved to a central position with respect to the arms 34 because of the inward inclination of these arms. The arms 34 then serve to prevent any sidewise movement of the bottoms of the containers and the top engaging element 63 serves a similar purpose for the tops of the containers.

The caps of crown type applied to all sizes of containers are, of course, all of similar diameter and a single type of top engaging head 63 will therefore suffice for all types of containers. However, bottles of various makes and sizes vary in body and base diameter but a wide range of bottles can obviously be readily centered and clamped upon the platform structure 31 illustrated herein. As has been stated above, if a bottler only intends to handle one size and type of bottle, he may equip the machine with bottle centering plates such as indicated at 66 but this is not ordinarily necessary.

It will be noted from Figure 1 that because of the slot and pin connection between chain 31 and shaft 20, the rod 89 and shaft can be readily adjusted during manufacture so as to obtain the proper degree of turning movement of each container supporting element. A very economical

and readily adjustable connection is thereby provided.

The terminology used in the specification is for the purpose of description and not of limitation, 5 the scope of the invention being indicated in the claims.

We claim:

1. In a mixing apparatus, a base, a rotary table, a plurality of members carried by and vertically reciprocable with respect to said table, cam means on said base to reciprocate said members, container supporting elements journaled upon said table for rotation with respect thereto, and a flexible strap connection between each 15 of said members and said container supporting elements so that the supporting elements will be rotated in a vertical plane upon vertical movement of said members.
2. In a mixing apparatus, a base, a rotary table, 20 a plurality of members carried by and vertically reciprocable with respect to said table, cam means on said base to reciprocate said members, container supporting elements journaled upon said table for rotation with respect thereto, and an adjustable flexible strap connection 25 between each of said members and said container supporting elements so that the supporting elements will be rotated in a vertical plane upon vertical movement of said members.
3. In a mixing apparatus, a base, a rotary table, 30 a plurality of members carried by and vertically reciprocable with respect to said table, a plurality of horizontally arranged shafts journaled upon said table, container supporting elements fixed to said shafts, and flexible strap elements extending between said shafts and said reciprocable members so that the shafts will be rotated in accordance with the reciprocation of 35 said members.
4. In a mixing apparatus, a base, a rotary table, 40 a plurality of members carried by and vertically reciprocable with respect to said table, a plurality of horizontally arranged shafts journaled upon said table, container supporting elements fixed to said shafts, flexible elements extending between said shafts and said reciprocable members so that the shafts will be rotated in accordance with the reciprocation of said members, and means associated with said shafts and flexible elements to 45 guide the latter about said shafts.
5. In a mixing apparatus, a base, a rotary table, 50 container supporting elements journaled for rotation with respect to said table, means to rotate said elements, locking means movable on said rotary table to engage said elements to hold the latter stationary with respect to said table, and cam means on said base to control said locking means.
6. In a mixing apparatus, a rotary table, container supporting elements journaled for rotation 55 with respect to said table, said container supporting elements including reciprocable container clamping arms, means reciprocable in said table to engage said elements to move said arms, said means being retractable from said elements to permit rotation of the latter with respect to said table.
7. In a mixing apparatus, a rotary table, container supporting elements journaled for rotation 60 in a vertical plane with respect to said table, said container supporting elements including longitudinally reciprocable clamping arms, means to actuate said arms to clamping position, plungers reciprocable in said table, and means extending 65 along the path of rotation of the table to move 70

said plungers into engagement with said clamping arms to move the latter to non-clamping position.

8. In a mixing apparatus, a stationary table, a rotary table, container supporting elements on said rotary table, means to transfer containers between said stationary table and said container supporting elements during rotation of said rotary table, said container supporting elements including flared guiding plates formed to define the path of transfer of a container.

9. In a mixing apparatus, a rotary table, container supporting elements journaled for rotation with respect to said table, said elements comprising a body portion and a top clamping arm reciprocable with respect thereto, a rotatable container top engaging element in said clamping arm, said body portion including a rotatable cup element, means on said clamping arm to limit movement of the upper part of a container and means on said body portion to limit movement of the lower part of the container.

10. In a mixing apparatus, a base, a rotary table, a plurality of container supporting elements on said table, means to deliver containers to said elements during movement of said rotary table including a fixed guide plate, and resilient means carried by said base arranged to cooperate with said delivery means and adapted to engage the containers to center the same on said elements.

11. In a mixing apparatus, a base, a rotary table, container gripping elements journaled for spinning movement on said table, a wheel journaled on said base, means to drive said wheel, said wheel being adapted to be engaged by said gripping elements to cause the latter to spin, and means on said wheel to contact with the containers and move them to centered position in the gripping elements.

12. In a mixing apparatus, a base, a rotary table, container supporting elements journaled for rotation with respect to said table, said container supporting elements including reciprocable

5 container clamping arms, members reciprocable in said table to engage said elements to move said arms, cam means fixed on said base to move said reciprocable members, and means moving with said table to support said reciprocable members while the latter are not in engagement with said cam means.

13. In a mixing apparatus, a container support comprising a base for receiving the bottom of a 10 container, a head movable toward and from the base and adapted to engage the top of the container, said base being adapted to receive containers of various diameters and comprising an upwardly facing cup-like member having side walls 15 extending inwardly and downwardly from its top edge, and a platform yieldably mounted substantially centrally within the side walls of the cup-like member and normally retained substantially flush with the top edge of said member, said platform having substantially equidistantly spaced peripheral portions alternating with side wall portions of said cup-like member.

14. In a mixing apparatus, a base, a rotary table, container supporting elements journaled for rotation with respect to said table, means to rotate said elements, locking means vertically reciprocable in said rotary table to hold said elements stationary with respect to said table and cam means on said base to control said locking means.

15. In a mixing apparatus, a base, a rotary table, a plurality of container supporting elements on said table, means to deliver containers to said elements during movement of said rotary table comprising a container feeding element and a guide plate, and means spaced above said delivery means to engage the upper portions of containers to center the same on said container supporting elements.
